RADIATOR

Filed June 16, 1930

Joseph W. Pate. Inventor

Eustaford

Attorney

UNITED STATES PATENT OFFICE

JOSEPH W. PATE, OF BIRMINGHAM, ALABAMA

RADIATOR

Application filed June 16, 1930. Serial No. 461,577.

This invention relates to radiators and an object of the invention is to provide a radiator adapted for the use of steam, hot water or other heating fluid and an object of the invention is to provide a radiator in which better circulation of air therethrough may be provided than is possible with known radiators.

A further general object is to so construct a radiator as to secure better heat radiation than is possible with known radiators.

Other objects and advantages will become apparent as the description proceeds.

Referring to the accompanying drawings, which are made a part hereof and on which similar reference characters indicate similar parts,

Figure 1 is a front elevation of the radiator, Figure 2, a view of the left hand end as seen on line 2—2 looking in the direction of the arrows,

Figure 3 is a section on line 3—3 of Figure 1, looking to the right as indicated by the arrows,

Figure 4, a section on line 4—4 of Figure 2, the view indicating a section through two units instead of a single end unit.

In the drawings numerals 10 and 11 indicate respectively the inlet and outlet units of a radiator. The unit 10 consists of inlet column 12 to which is attached a fluid inlet pipe 13. The unit 10 further consists of vertical pipes 14 and 15, the pipes 12, 14 and 15 each being provided with a plurality of fins 16 to provide for heat radiation. The pipe 14 is connected at its upper and lower ends to the pipe 15 by means of pipes 17 and 18. Pipe 19 also connects the intermediate portions of the pipes 14 and 15.

Passage of heating fluid from the pipe 12 into the pipes 14 and 15 is controlled by means of a valve 20. The outlet section 11 is provided with three columns 21, 22 and 23 which are connected together by pipes 24, 25 and 26. An outlet pipe 27 is connected to the pipe 23 by a pipe 28. The units 10 and 11 are each complete in themselves and are provided with ports 29, 30, 31 and 32 by means of which other units are attached to them. Any number of intermediate units 33 may be secured between the inlet and outlet units 10 and 11.

The intermediate units 33 are similar in all respects to the outlet unit 11 except that they are not provided with the outlet pipe 27 nor the connection 28 between the outlet pipe and the upright column 23. The units 33 therefore have not been further shown in detail as their structure may be clearly understood from that shown in Figure 2.

The units may be secured together in any suitable way as for example as shown in Fig. 4 by means of connections 34. The front of each unit is provided with a plate 35 which may be attached to or made integral with the pipe 12. The front plate 36 of the unit 11 may likewise be attached to or made integral with front pipe 21. This front plate 36 is provided with an opening at 37 and the sum total of the openings 38 cooperate to define a rectangular slot 39 at the lower front of the radiator. The front plates 35 and 36 unite to form a front plate 40 as shown in the front view in Figure 1. For the purpose of ornamentation and to give the effect of a panel, a ridge 41 may be provided in the plates.

An opening 42 is provided also at the upper ends of the plates 35 and 36 to provide a rectangular slot at the top of the radiator. A baffle plate 43 is secured at the upper end of each of the rear columns 15 and 23. The plate 43 may be attached to or made integral with the pipes. As indicated plates 44 and 45 may be attached to the rear of the pipes 15 and 23 and these being edge to edge with each other to define the rear wall of the radiator. From the construction so far defined it will be seen that the units are secured together to define a flue through which air to be heated may pass, this air entering the radiator at the elongated slot 38 passing up around the radiator columns and out through the elongated slot 42 at the top of the radiator, the air being deflected outwardly by means of the plate 43.

From the construction defined it will be seen that a manifold 46 is defined by the connecting pipes 29 and 31 together with the intermediate connections at the top of the radiator and a similar manifold by the connections 30 and 32 and intermediate connections at the bottom of the radiator.

radiator. These manifolds are out of the path of travel of the air and so do not tend to obstruct its travel. A free circulation therefore is provided through the radiator. In order to provide for better heat radiation by providing better contact with the pipes the fins 16 are placed in staggered relation.

5 It will be obvious to those skilled in the art that various changes may be made in my device without departing from the spirit of 10 the invention and therefore I do not limit myself to what is shown in the drawings and described in the specification, but only as indicated in the appended claims.

15 Having thus fully described my said invention, what I claim as new and desire to secure by Letters Patent, is:

1. A radiator comprising end and intermediate sections secured together, each section having a vertically extending pipe, pipes 20 parallel with, spaced from, and having the ends thereof connected with said vertical pipe intermediate the ends thereof, plates secured to the front and back of said sections having 25 their edges in alignment and contacting thereby forming a front and a back wall for said radiator, said front wall terminating at the ends of said second pipes thereby forming a draft flue adapted to circulate air through 30 the radiator to absorb heat therefrom, substantially as set forth.

2. A radiator comprising end and intermediate sections secured together, each section having a vertically extending pipe, pipes 35 parallel with, spaced from, and having the ends thereof connected with said vertical pipe intermediate the ends thereof, plates secured to the front and back of said sections having their edges in alignment and contacting thereby forming a front and a back wall for said radiator, said front wall terminating at the ends of said second pipes thereby forming a draft flue adapted to circulate air through the radiator to absorb heat therefrom, and deflecting plates extending horizontally from the upper ends of said vertically extending pipes to the front edge of 40 said radiator serving to deflect the heated air substantially as set forth.

45 50 In witness whereof, I have hereunto set my hand at Birmingham, Alabama, this (twelfth) 12th day of June, A. D. nineteen hundred and thirty.

JOSEPH W. PATE.
